UNITED STATES PATENT OFFICE

133,940

DESIGN FOR A WRAPPING PAPER OR SIMILAR ARTICLE

Ladislas Medgyes, New York, N. Y., assignor to Helena Rubinstein, Inc., New York, N. Y., a corporation of New York

Application July 14, 1942, Serial No. 107,536

Term of patent 7 years

To all whom it may concern:

Be it known that I, Ladislas Medgyes, a citizen of Hungary, and residing in New York city, New York, have invented a new, original, and ornamental Design for a Wrapping Paper or Similar Article, of which the following is a specification, reference being had to the accompanying drawing, forming part thereof.

The figure is a plan view of a wrapping paper or similar article showing my new design.

I claim:

The ornamental design for a wrapping paper or similar article, as shown.

LADISLAS MEDGYES.
